FREEZING MACHINE

William S. Shaw, Boyne City, Mich.

Application October 15, 1930, Serial No. 488,817

4 Claims. (Cl. 62—104)

The present invention relates to a machine for quick-freezing; relating particularly to mechanical improvements which enable the quick-freezing of packaged goods of various dimensions in the 5 same machine.

One of the objects of the invention is to provide freezing means consisting of a plurality of hollow metallic plates arranged for reciprocal movement relative to each other, whereby the articles to be 10 frozen may be imprisoned between said plates, which latter are kept by means of brine, or other refrigerating medium, at an extremely low temperature; whereby quick-freezing of the said articles will be effected.

15 A further object of the invention is to provide a machine comprising a plurality of hollow plates connected with each other for the flow of refrigerating fluid therethrough in series, in cooperation with a similar set of plates arranged above the 20 first-mentioned set, the upper set of plates being arranged for lifting and lowering, so as to take packages of goods to be frozen of various sizes.

The present invention is particularly applicable 25 to the freezing of comestibles, such as fish and meat, particularly when same is arranged in the form of merchantable packages of more or less regular dimensions; that is to say, the goods have been packed with a minimum of air spaces and are substantially of a flat surface capable of contacting 30 with highly chilled metallic heat-conducting plates or the like.

The processes of freezing have commercially 35 been divided into methods of mere chilling, of sharp-freezing and quick-freezing, these terms now being so well understood in the refrigerating art that a discussion thereof in the present patent, which relates to mechanical means for carrying out quick-freezing, would, at the present state 40 of the art, be a superfluity. The machine which I have invented consists of a number of plates which are either hollow or provided with internal tubing for the circulation of brine or the like, which plates are rigidly supported in a horizontal 45 position and are connected in multiple or series, so that the brine may circulate therethrough, thereby lowering their temperature to any desired degree. Supported above the first set of plates is a similar set which, however, is provided with 50 means, such as hydraulic rams, for raising or lowering said upper plates, so that when packages of goods to be frozen are resting on the stationary lower plates the upper plates may be lowered upon the goods with sufficient pressure to insure good contact, this contact being maintained until the 55 goods have been frozen to the desired degree.

In order to insure proper spacing of the goods and to facilitate loading the individual sets of plates with said goods, it is also within contemplation of my invention to provide the upper or lower plates, or both, with hollow flanges abutting said plates and connected therewith at right angles thereto, this feature, however, not being indispensable to the proper operation of my machine.

10 My invention also contemplates a method of freezing which comprises compressing comestibles between two highly chilled plates, thus to insure good contact and to enable the goods to be frozen with sufficient rapidity to eventuate quick-freezing thereof.

15 For a better understanding of my invention, I have appended hereto a number of drawings, in which:

Figure 1 is a diagrammatic side elevation of a 20 section of my machine in only sufficient detail to enable a proper understanding of its principles of operation, said drawing not to be taken as a working drawing;

Fig. 2 is a top plan view of the lower set of 25 horizontal plates;

Fig. 3 is an elevational detail view of means for 30 connecting the upper plates, partially in section;

Fig. 4 is a top plan view of the upper plates showing partially in section the connecting rod 35 of the ram that raises and lowers said plates; and

Fig. 5 is a sectional view of the hydraulic ram 40 employed for lifting and lowering the upper plates.

Referring to the drawings, it will be seen that 45 the machine consists of a structural steel frame 10 which is suitably bolted or riveted together, and which supports a plurality of hollow plates 11 which are connected to each other in series (or in multiple, if desired) by means of the pipes 12. Suitable arrangements are made for circulating 50 through said hollow plates 11 a refrigerant, such as calcium chloride brine or liquid ammonia, which is allowed to expand in the plates, thereby greatly lowering their temperature. The plates are preferably made of steel or of a non-rusting 55 steel alloy, the plates being of sufficient strength to withstand internal pressure corresponding to evaporating ammonia, if that be the refrigerant employed. There is also provided a corresponding set of upper plates 13 quite similar in construction to the lower plates 11, these plates, however, being connected to each other from their upper surfaces by means of the pipes 14 and 15, the said pipes being interconnected by the return-bends 16; the said bends being supported 60

by means of hangers 17 which are secured to an upper member 10' of the structural steel frame aforesaid. The plates 13 are also provided, if desired, with downwardly extending flanges 14 which, when the plates 13 and 11 are placed down over the packages 18, will project behind said packages, so as to prevent access of atmospheric air to the sides thereof. These hollow flanges may extend on four sides of the plates, or only on two sides thereof; and may be omitted without departing from the spirit of my invention.

The upper plates 13 are connected by means of a rod 19 to the hydraulic ram broadly designated 15 by the reference numeral 20 and consisting of the housing 21 and the piston 22, as more completely shown in Fig. 5 already referred to. The device 20 is a standard and well known piece of apparatus, such as is used in hydraulic presses, 20 and comprises customary liquid (oil) inlets 23 and 24, whereby through the intermediation of proper valves (not shown) hydraulic lifting fluid may be placed on either side of the piston 22, thereby moving it in either direction—that is, up 25 or down. By virtue of the connection of the piston with the plate 13 the plate will, of course, partake of the movements of said piston. In order to enable the lifting of the plates 13 to take place without breaking their connections with the 30 pipes 14 and 15, provision is made for the telescoping of the pipe 15 to the connecting pipe 15' which is screwed into or welded to the upper plates 13. In order to prevent leakage of the refrigerant, standard glands 25 and packing 25' 35 are provided, as shown in Fig. 3, whereby vertical telescoping movement may be effected between the pipes 15 and 15'. In other words, when the plate 13 is lifted the pipe 15 will telescope into the pipe 15', as is illustrated in Fig. 1 where the 40 central plate 13 is shown in its raised position. It is believed that the operation will be sufficiently understood from an inspection of the drawings and this description.

I have not illustrated the brine-circulating, 45 ammonia-circulating and hydraulic fluid-circulating devices, as these are all standard and thoroughly well known in their respective arts and form no part of my present invention.

The lower plates are supported on the framework 50, preferably being thoroughly insulated therefrom in order to conserve refrigerating efficiency.

As indicated in Figs. 2 and 4 it will be seen that the plates 11 and 13 are provided on their 55 interiors with baffles 11' and 13' to insure a more perfect distribution of the refrigerant within the said hollow plates.

I also provide about the periphery of the plates, with the exception of the upper surface of the 60 lower plate and the lower surface of the upper plate, a suitable thermally-insulating lagging which prevents the accumulation of frost on the exposed parts of the plates and insures the more efficient operation of my machine.

Without limiting my invention in any way I 65 may state that I prefer to make the plates about 24 inches wide, 30 inches long and about 1½ to 2½ inches of internal diameter. I also contemplate providing my machine with from 10 to 20 70 sets of plates arranged in series, and also contemplate providing a second series of said plates alongside the first series, the entire machine being operated from a suitable aisle or corridor along each longitudinal side of the machine. In operating 75 the machine the operator places either the

packaged goods or unpackaged comestibles, which are preferably placed on trays so as to facilitate their handling, upon, say, a lower plate 11, whereupon the upper plate 13 is lowered until it contacts with the goods to be frozen, whereupon, by virtue of the circulation of the refrigerant, freezing takes place with considerable rapidity. While one set of comestibles is being frozen between a set of the upper and lower plates, the next adjacent set may be loaded, and so on, working from one end of the machine to the other until it is entirely loaded. At the end of this time it will usually be found that the set of plates first loaded has frozen the goods placed therein, so that by lifting the upper plate 13 these goods 15 may be removed and a new set placed therein. Thus continuous operation of the machine can be carried out successfully.

One of the striking advantages of the machine 20 is that goods of various dimensions may be frozen between the different sets of plates, a feature which has been absent from all previous freezing machines known to me, as, for example, machines in which the goods are placed in cans which are immersed in brine, or in machines operating by 25 the aid of a traveling refrigerated belt, as it is obvious that in such a belt-machine all the goods must needs be of the same dimensions, at least in one direction, as otherwise the larger goods only will make contact with both of the belts. 30 In my machine, on the contrary, comparatively thick packaged goods may be frozen in one set of plates while a much narrower set of goods may be frozen in an adjacent set.

A further advantage of my machine is that 35 the operation of the lifting and lowering of the plates is much less expensive than operation of the forward-moving complicated belt type of freezing-machine. In order that the upper plates 13 may be kept in proper alignment, and 40 also to insure a more accurate and equal distribution of the refrigerant, the pipes 14 and 15 and the return-bend 16 are duplicated for each plate; that is to say, each of the upper plates has two sets of pipes 15 and two sets of 45 pipes 14 as can best be realized by an inspection of Fig. 4. The lower plates 11 are also connected with duplicate pipes 12 and 12', as is clearly shown in Fig. 2.

The speed of circulating the brine or ammonia 50 is entirely governed by the rate of freezing desired, and no limitations are to be placed on my invention relative to this point.

As a matter of convenience, the lower set of stationary plates is placed at such an elevation 55 above the floor level of the room in which the machine is set up so that the plates may conveniently be charged by the operators, who, either by hand or mechanically, place the packed goods to be frozen upon the lower plates. The upper 60 plates may then individually be lowered until they make contact with the packaged goods, sufficient excess pressure being admitted to the upper portion of the cylinder 21 to exert any desired pressure upon the goods, thus insuring close contact 65 thereof with the plates. The flange, or flanges, 14 is preferably kept slightly shorter than the thickness of the packages of the goods. In loading the machine, to insure the proper placing of the goods, the plate 13 may be lowered into proximity of the lower plate, leaving, however, sufficient free space so that the goods may be freely pushed over the lower plate toward the downwardly projecting flanges of the upper plate, which thus serves as a guide to align the packages and to 75

insure their proper spacing. This also prevents the packages from becoming wedged between the flange and the lower plate. When the upper plate is then finally lowered into position the flange 5 will reach almost to the lower plate, thus keeping out warm air drafts which might interfere with the desired rapidity of the freezing.

When the goods have been frozen, the upper 10 plate is lifted high enough for the flanges to entirely clear the packages, which may then be removed with ease. If the packages are of the paraffined paper type there is no difficulty with the sticking thereof to the plate, but should this occur, they may readily be loosened by a blast of compressed 15 air from a small air hose or the like.

The pipes 14 and 15, when made sufficiently 20 large and rigid, will act as guides for the movable plates 13, thus keeping the same in proper horizontal alignment. If desired, however, additional 25 vertical guides may be provided.

While the raising and lowering of the upper 30 plates may be accomplished by manual control of the operating valves of the hydraulic lifting system, it will also be within the scope of my invention to provide automatic timing mechanisms 25 for effecting said operations at given intervals, thus rendering the operation of my machine more certain, and preventing under- or over-freezing of the goods.

In commercial practice, it will be advisable to 35 lag or insulate the structural steel framework of the machine in order to prevent the condensation and freezing of moisture thereon, but all such mechanical details are expedients well known to those skilled in the refrigeration arts, and need not, therefore, be described in detail herein, as a thorough understanding of the patentable features of my invention can be had from the description hereinabove in connection with the 40 drawings.

As already pointed out, the essential features 45 of my invention are found particularly in the cooperation between a set of stationary and a set of vertically movable plates, coupled with means for lifting and lowering said latter plates, and means for adding to the pressure exerted on the goods by the upper plates by hydraulic rams or their equivalents.

It is also to be considered within the scope of 50 my invention to double-deck the machine, i. e., to provide two sets of stationary and of movable plates superimposed, so as to save floor space.

What I claim is:

1. A quick-freezing machine comprising, in 55 combination, a framework, a plurality of stationary horizontally disposed hollow plates mounted rigid-

ly thereon, a plurality of hollow movable horizontally disposed plates positioned above said stationary plates, means for raising and lowering said movable plates, connections between said lower plates for passing refrigerating fluid therethrough telescoping connections for permitting similar operation with the movable plates, said connection comprising vertically disposed pipes attached to the upper surface of said plates, and vertical pipes telescoping into the latter, said second set of pipes being interconnected by return-bends that are supported on said framework. 10

2. A quick-freezing machine comprising, in combination, a framework, a set of hollow metallic plates rigidly attached to said framework, pipe 15 connections between said plates allowing of circulation of refrigerant through the same, a set of horizontally positioned hollow plates movable in a reciprocating relationship with said first-mentioned plates, means, comprising hydraulic rams, 20 for raising and lowering said movable plates, vertical pipes and return-bends connecting said movable plates, and means for permitting the movement of said movable plates without interrupting their interconnection with each other. 25

3. A quick-freezing machine for freezing comestibles that are contained in packages having substantially rectangular form which comprises, in combination, a framework a plurality of stationary hollow metallic plates rigidly attached 30 thereto, pipes connecting said plates for permitting circulation of brine therethrough, a second set of horizontally disposed plates, hydraulic lifting means secured to the upper part of said framework, means connecting said lifting means 35 with said second set of plates, there being one lifting means for each of said plates, a plurality of return-bends attached to said frame, vertical pipes connecting said bends with said movable plates, and means for permitting telescoping action 40 between said movable plates and said latter pipes. 45

4. A quick-freezing machine comprising, in combination, a framework, a set of hollow metallic plates rigidly attached to said framework, pipe 45 connections between said plates allowing of circulation of refrigerant through the same, a set of horizontally positioned hollow plates movable in a reciprocating relationship with said first-mentioned plates, means for raising and lowering 50 said movable plates, vertical pipes and return-bends connecting said movable plates and means for permitting the movement of said movable plates without interrupting their interconnection with each other. 55

WILLIAM S. SHAW.
